ABSTRACT

A pivoting device for a winding weight of an automatic watch movement comprising a frame element support with a circular opening, a one piece boss rotatively fit in the circular opening and attached to the winding weight, the boss containing an eccentric stud for driving a winding train.

FIG. 1

FIG. 2

PIVOTING DEVICE FOR THE WINDING WEIGHT OF AN AUTOMATIC WATCH

The present invention relates to a pivoting device for the winding weight of an automatic watch, one of the parts of which has a cylindrical sliding surface and two opposed, annular, axial banking surfaces, and the other part of which consists of a flat ring disposed around the sliding surface and between the banking surfaces.

A device of this type is described in Swiss Pat. No. 485,257. It was designed with the object of providing a thin device capable of being set in place on the watch movement and removed as a unit. In this known device, the winding weight has a center aperture into which a ring-shaped winding-weight pinion is fitted. This ring carries an inner part which constitutes a second flat ring guided axially between two fixed discs and around a cylindrical interposed part. Thus the pinion is situated above the oscillating-weight support to which the discs and the interposed part are fixed.

It is the object of the present invention to simplify the manufacture of pivoting devices of this type and to reduce their overall axial height still further while retaining their advantages.

To this end, the device according to the invention, of the type defined above, is characterized by a one-piece boss having the sliding surface and one of the axial banking surfaces and being rigidly fixed to another element of the same part of the bearing having the other annular axial banking surface, the boss constituting the first member of the automatic winding train, and the flat ring constituting part of an oscillating-weight support intended to be fixed to the frame of the movement.

Pivoting devices for winding weights are also known which include ball bearings. In certain types of bearings, a boss fixed to the winding weight has a peripheral collar which, together with an upper ring likewise kept in place by the boss, constitutes the inner ball-race of the bearing. This design is completely different from the one which is the subject of the present invention.

The accompanying drawing shows two embodiments of the pivoting device according to the invention, by way of example.

FIGS. 1 and 2 of the drawing are axial sectional views.

The pivoting device shown in FIG. 1 ensures the pivoting of a winding weight in an automatic watch movement. It is composed of three parts: a boss 1, a banking 2a, and an oscillating-weight support 3. The banking 2a forms part of the winding weight 2. The boss 1 is a generally cylindrical-shaped part provided with a rim 4 projecting laterally from its lower portion. The upper annular face of the rim 4 forms a first axial banking surface of the device described. Extending from the inner edge of this annular surface is a cylindrical bearing surface 5 which is limited at its upper end by an annular shoulder 6. The boss 1 further has an upper prolongation 7 which extends axially from the inside edge of the shoulder 6. Because of its simple shape, the boss can be produced by stamping, and a stud 8 which projects from its lower face in an off-center position likewise results from the stamping operation. Hence the manufacture of the boss 1 is extremely simple and inexpensive.

The support 3 is a frame element which can be fixed to one of the bars of the movement by conventional means. It has a circular opening, the diameter of which is adjusted to that of the bearing surface 5. In the vicinity of this opening, its thickness is reduced so as to be slightly less than the height of the bearing surface 5. If need be, the support 3 may serve to pivot elements of the winding train. As usual, the winding weight 2 is sector-shaped with a center aperture 9 made in a thickened annular portion 2a of the weight 2, having a thickness equal to the height of the prolongation 7.

To assemble the device described, the bearing surface 5 of the boss 1 is first engaged in the opening of the support 3. Then the prolongation 7 is driven or clinched or riveted into the aperture 9. The oscillating-weight support, held between the upper face of the rim 4 and the lower face of the thick portion 2a of the weight 2, is then fixed to the frame of the movement, e.g. on the train bar. The stud 8 then projects between the weight support and the movement so as to ensure the driving of the winding train in a manner known per se. The lower annular surface of the thickened portion of the winding weight, which is a plane surface, is on a level with the top of the shoulder 6 and forms the upper axial banking surface cooperating with the weight support. Opening out of this surface are holes 10 which are distributed around the boss and make it possible to lubricate the sliding surfaces of the bearing.

FIG. 2 shows a second embodiment of the pivoting device according to the invention. This embodiment differs from the first one chiefly in that the boss 11 is connected to the winding weight 12 by a screw 20. The boss 11 has a threaded center aperture 21 in which the screw is engaged. The flattened prolongation 17 serves to center the boss in the center aperture 19 of the weight 12. The shoulder 16, the cylindrical bearing surface 15, the projecting rim 14, and the winding-weight support 13 have the same functions as the corresponding parts in the first embodiment. The holes 10 likewise serve for the lubrication of the pivoting and banking surfaces. However, the means provided here for driving the winding train consists of a toothed edge 18 which is contrived in the outer edge of the projecting portion 14.

As compared with the first embodiment, the one shown in FIG. 2 has the advantage that the winding weight can be separated from the weight support. However, this advantage entails a somewhat more complicated manufacture.

As other variations of the constructions described above, it is also possible to conceive of combinations of each of the two modes of driving described with the fastening means shown in combination with the other. Thus, for instance, the weight 12 of FIG. 2 could also be driven or clinched on the boss 11 as shown in FIG. 1.

If need be, depending upon the material chosen for the boss and the winding-weight support, it might be advantageous to have the prolongations 7 and 17 made of a different material from the weights 2 or 12. The prolongations 7 or 17 would then consist of a detachable flat ring.

What is claimed is:

1. A pivoting device for a winding weight of an automatic watch movement, comprising a winding weight support having a flat ring shaped portion with a circular opening therein, said support being intended to be fixed to the frame of said movement, a one-piece boss

including a cylindrical sliding surface, a first banking surface and means for driving a winding train of said movement, and further a member, integral with said winding weight, rigidly secured to said boss and including a second banking surface, said second banking surface extending opposite said first banking surface, said ring shaped portion extending between said banking surfaces and said circular opening engaging said cylindrical sliding surface.

2. A device according to claim 1, wherein the boss has an eccentric driving stud projecting from its lower face.

3. A device according to claim 1, wherein the boss has a toothed coaxial with the weight and is intended to drive the winding train.

4. A device according to claim 1, wherein the boss has a plane annular shoulder and a prolongation projecting above said shoulder, and wherein the boss is fixed to the winding weight in such a way that said prolongation is engaged in an aperture in the weight, a plane annular surface which limits said aperture resting upon said shoulder.

5. A device according to claim 4, wherein the boss is permanently fixed to the weight by being driven in or clinched or riveted.

6. A device according to claim 4, wherein the boss is fixed to the weight by a screw engaged in said prolongation.
